US00D704149S

(12) **United States Design Patent**
Azzola et al.

(10) **Patent No.:** US D704,149 S
(45) **Date of Patent:** ** May 6, 2014

(54) **CIRCUIT BREAKER COMPONENT**

(75) Inventors: **Lucio Azzola**, Bergamo (IT); **Giovanni Frassinetti**, Bergamo (IT)

(73) Assignee: **ABB S.p.A.**, Milan (IT)

(**) Term: **14 Years**

(21) Appl. No.: **29/416,359**

(22) Filed: **Mar. 21, 2012**
